CLAIM

The ornamental design for a face covering cap clip, as shown and described.

DESCRIPTION

FIG. 1 is a front perspective view of a face covering cap clip in accordance with a first embodiment of the present invention.

FIG. 2 is a front view of the embodiment shown in FIG. 1. FIG. 3 is a right side view of the embodiment shown in FIG. 1.

FIG. 4 is a rear view of the embodiment shown in FIG. 1. FIG. 5 is a left side view of the embodiment shown in FIG. 1.

FIG. 6 is a bottom view of the embodiment shown in FIG. 1.

FIG. 7 is a top view of the embodiment shown in FIG. 1. FIG. 8 is a front perspective view of a face covering cap clip in accordance with a second embodiment of the present invention.

FIG. 9 is a rear view of the embodiment shown in FIG. 8. FIG. 10 is a right side view of the embodiment shown in FIG. 8.

FIG. 11 is a front view of the embodiment shown in FIG. 8. FIG. 12 is a left side view of the embodiment shown in FIG. 8.

FIG. 13 is a bottom view of the embodiment shown in FIG. 8; and,

FIG. 14 is a top view of the embodiment shown in FIG. 8.
